UNITED STATES PATENT OFFICE

2,246,249

WINDOW SUPPORTING STRUCTURE

Alfred H. Haberstump, Detroit, Mich., assignor to
 The Murray Corporation of America, Detroit,
 Mich., a corporation of Delaware

Application December 14, 1938, Serial No. 245,575

1 Claim. (Cl. 296—44.5)

The invention relates generally to motor vehicles and it has particular relation to the guiding of the vertically movable windows in the doors of such vehicles.

In certain respects the invention constitutes an improvement over that embodied in my copending application for patent, entitled "Glass run guide channels", issued as Patent No. 2,214,328 on Sept. 10, 1940.

One object of the present invention is to provide an improved arrangement including vertically extending guideways on the door and cooperating guide members on the window, wherein the guide members on the window are tilttable in the plane of the latter so that they may accommodate themselves readily to the paths defined by the guideways.

Another object of the invention is to provide improved guide means on the window adapted to engage guideways on the door, wherein each guide means at the side edge of the window is in the form of a carriage tilttable in the plane of the window, so that the carriage may readily be altered in position to compensate for variations in the guideway.

Another object of the invention is to provide an improved guide means at each side edge of the window which is in the form of a single carriage tilttable in the plane of the window and which has vertically spaced means for contacting the guideways, so as thereby to simplify the structure and facilitate manufacturing and assembling operations.

Another object of the invention is to provide improved means that are inexpensive and durable for resiliently holding the guideways against the guide means, so as thereby to prevent looseness and noise.

Another object of the invention is to provide improved means for guiding a window in its upward and downward movement, which compensates for the usual inset in the rear edge of the rear vehicle door.

Another object of the invention is to provide improved means for vertically guiding a window in a vehicle door, wherein the guiding means is offset transversely to the plane of the window.

Other objects of the invention will become apparent from the following specification, from the drawings to which it relates, and from the claim hereinafter set forth.

For a better understanding of the invention, reference may be had to the drawings, wherein:

Figure 1 is a fragmentary, elevational view, partly in section, illustrating a vehicle door pro-

vided with window guiding means at its front edge as constructed according to one form of the invention;

Fig. 2 is a cross-sectional view taken substantially along the line 2—2 of Fig. 1;

Fig. 3 is a view on the order of Fig. 1, but illustrating the window guiding means at the rear edge of the door;

Fig. 4 is a cross-sectional view on a larger scale taken substantially along the line 4—4 of Fig. 1;

Fig. 5 is a cross-sectional view on a larger scale taken substantially along the line 5—5 of Fig. 1;

Fig. 6 is a detail view on a larger scale, showing the roller supporting carriage at the front edge of the window, as seen in Fig. 1;

Fig. 7 is a cross-sectional view on a larger scale, taken substantially along the line 7—7 of Fig. 1;

Fig. 8 is a cross-sectional view on a larger scale, taken substantially along the line 8—8 of Fig. 3;

Fig. 9 is a cross-sectional view on a larger scale, taken substantially along the line 9—9 of Fig. 3;

Fig. 10 is a detail view illustrating the roller supporting carriage for the rear edge of the window, as seen in Fig. 3;

Fig. 11 is a fragmentary, elevational view, showing the guideway and guiding means for the rear edge of the window as constructed according to another form of the invention;

Fig. 12 is a cross-sectional view on a larger scale, taken substantially along the line 12—12 of Fig. 11;

Fig. 13 is a cross-sectional view on a larger scale, taken substantially along the line 13—13 of Fig. 11;

Fig. 14 is a fragmentary, elevational view, partly in cross-section, of the window guiding means at the front edge of the door, as constructed according to another form of the invention;

Fig. 15 is a cross-sectional view on a larger scale, taken substantially along the line 15—15 of Fig. 14;

Fig. 16 is a fragmentary, elevational view, partly in cross-section, showing guiding means for the front edge of the door, and illustrating particularly, an improved resilient mounting as constructed according to another form of the invention;

Fig. 17 is a cross-sectional view on a larger scale, taken substantially along the line 17—17 of Fig. 16;

Fig. 18 is a fragmentary, elevational view, partly in cross-section, showing improved means for guiding the rear edge of the window as con-

structed according to another form of the invention; and

Fig. 19 is a cross-sectional view on a larger scale, taken substantially along the line 19—19 of Fig. 18;

Referring to Figs. 1, 2, and 3, a rear door of the vehicle is indicated generally at 10, and, as will be understood, a door of this character has a well for receiving a vertically slideable window 11. This well is formed by inner and outer panels 12 and 13 that may be secured together along their front, rear, and bottom margins in the manner explained in the copending application now Patent #2,214,328 previously mentioned. A channel member 15 extends along the rear, top, and front edges of the window, and at the front this channel has a downward projection 16. Also, a channel member 17 embraces the lower edge of the glass and this member is secured to a depending roller guide 18 adapted to engage a regulator.

Now directing attention particularly to the front edge of the door, as shown by Fig. 1, and to Figs. 4, 5, and 6, showing details, the projection 16 at the front edge of the window receives a roller carriage 19 that is in the form of a channel having vertically spaced rollers 20 and 21 mounted on pins 22 and 23 connecting the legs of the channel. This carriage is pivotally mounted in the projection 16 by means of a pin 24 extending through openings 25 and 26 formed, respectively, in the legs of the projection 16 and in the legs of the carriage channel. The pin, as best shown by Fig. 4, may comprise an outer tubular element 28 and a stem threaded thereto, and from this it is apparent that the pin may be readily inserted and properly tightened by relatively turning the two parts of the pin.

As shown by Figs. 5 and 6, the base portion of projection 16 has vertically spaced slots 30 which allow the rollers 20 and 21, respectively, to project therethrough. For reinforcing the projection 16, a bracket is employed and this may comprise two parts 33 and 34 that are connected by screws or bolts 35. The part 33 is welded to the channel at the lower edge of the window while the part 34 extends into the channel projection 16 and is welded to the latter although it is to be observed that pin 24 in passing through such part 34 may be used as the sole connection, if desired.

As shown by Fig. 5, the projecting rollers 20 and 21 rotatably engage a grooved channel guideway 36 which is fixed against vertical movement in a channel 37, that in turn may be secured to the door panel 12. The manner in which the channel 37 may be secured to such panel may correspond to that disclosed in the previously mentioned copending case now Patent #2,214,328. The guideway 36 is free to move rearwardly and forwardly and is resiliently urged against the peripheries of the rollers by means of a sinuous leaf spring 38, which seats against the base of the channel 37. This spring is prevented from moving vertically by employing inturned lips 40 and 41 at the lower and upper ends of the channel 37, as shown by Fig. 1. For preventing vertical movement of the guideway 36 in the channel 37, one or more lips 43 (Fig. 5) may be turned in from one leg of the channel 37 and into a slot 44 formed in the adjacent leg of the guideway 36. This slot permits forward and rearward movement of the guideway in the channel, but the horizontal edges of the slots prevent relative vertical movement thereof. Inturned edges 45 and 46 at the front ends of the legs of guideway 37

retain the guideway within the channel, but it will be observed that the arrangement is such that the guideway may freely move in a forward or rearward direction within limits.

5 From the foregoing description, it will be appreciated that the pivotal mounting of the carriage 19 permits the rollers 20 and 21 to remain in contact with the groove in guideway 36, regardless of usual variations, and that such rollers 10 provide vertically spaced supports that prevent cocking of the window. By providing both rollers on a single carriage and pivotally mounting the carriage in the manner described, the guiding means and the assembling thereof are very much simplified.

In order to provide additional anti-rattle means engageable with the window at the upper end of the window well, a resilient rubber roller 20 47 may be provided at each side of and in engagement with the window channel 15, as shown by Fig. 7. Each of these rollers is vulcanized on a pin 48 and the pin is journaled at its ends in openings formed in tongues 49 struck in from the legs of the guideway 36.

25 At the rear edge of the door, as shown by Figs. 8, 9, and 10, a triangular bracket 52 is provided that is secured by rivets or the like 53 to the base portion of the channel member 17. This bracket has a vertically arranged flange at 30 its front edge which projects into a vertically arranged carriage channel 55. These parts are pivotally connected by means of a pin 56 projecting through openings 57 and 58, respectively, formed in the flange and the channel. Thus, the 35 channel is rockably mounted within limits governed by the projection of the flange into the channel. As best shown by Figs. 8 and 9, the channel 55 at its upper and lower ends has pins 62 and 63 connected thereto, which at their outer 40 ends support rollers 64 and 65. These pins, in passing through the channel 55, are prevented from interfering with the flange 54 by providing cut-out notches 66 and 67 that allow the pins to move relative to the flange.

45 The rollers 64 and 65 engage a guideway 68, which is secured to the door panel 12, and it may be noted that this guideway is offset with respect to the plane of the glass and that the rollers likewise are offset so that the guiding means at the rear edge of the window is offset with respect to the plane of the glass. It may be noted also that the bracket 52 disposes the carriage forwardly of the rear extremity of the window and this is desirable so that the lower 55 end of the guideway clears the inset ordinarily present at the lower, rear edge of the door.

Accordingly, the window at the rear thereof is 60 positively supported by means of a pivotal carriage that engages a stationary guideway at vertically spaced points. By providing the leaf spring in the front channel and tiltable carriages in both guideways, it will be apparent that a closely fitting arrangement is obtained since the spring constantly urges the front guideway towards the rear guideway and since the vertically spaced roller contacts are maintained regardless of any irregularity in the guideways.

In Figures 11, 12, and 13, which relate to an arrangement somewhat on the order of that 65 shown by Fig. 3, a channel 75 is provided and this is secured to the panel 12 by means of a bracket 76 welded to one leg of the guideway and secured at its ends by screw fastening devices 77 to the panel. This bracket is provided at the upper end of the channel and a connection may

be provided at the lower end of the channel in the form of a metal bracket 18 secured by screw fastening devices 19 to the panel. The channel has a leaf spring 81 like that previously described, and this spring presses against a guideway 83 disposed in the channel, and which is slidable within limits in a direction parallel to the legs of the channel. A struck-in lip on one leg of the channel, disposed in an enlarged slot 85 in one leg of the guideway 83, serves to hold the latter against vertical movement in the channel, but it will be understood that the slot 85 is sufficiently large to allow substantial forward and rearward movement of the guideway. The guideway cooperates with roller carriages in the same manner as shown by Figs. 9 and 10 and the roller carriage and bracket connecting the carriage to the window are essentially the same as that shown in these figures, excepting that the carriage pivot pin corresponds to that shown by Fig. 4.

Now referring to Fig. 14, the window and roller carriage employed in this structure are the same as that shown by Fig. 1, but instead of using a channel 37 extending substantially from the top to the bottom of the door well, as shown in the latter figure, only short channels 80 and 81 are provided adjacent the top of and bottom of the well. Each of these channels is of the same form as the channel 37 provided in Fig. 1, but only a short leaf spring 82 is employed on the base of the channel and each of these springs is retained against vertical removal by inturned lips 83 and 84 at the ends of the base of the channel. Vertical movement of the guideway 36 is prevented by lips such as 85 on the guideway which project into sufficiently large notches in one leg of the channels so as to permit the required resilient movement of the guideway. Otherwise, the detailed structure is like that shown by Fig. 4 and the tilttable carriage, having the rollers engaging the grooved base of the guideway, are the same and like numerals may be employed to identify the parts.

In Figs. 16 and 17, the same tilttable carriage and means for mounting the carriage on the window are employed as described in connection with Figs. 1 and 14. For resiliently holding the guideway in this case, an upper bracket 90 and a lower bracket 91 are provided corresponding substantially in positions to the brackets 80 and 81 in Fig. 14. Each of these brackets, as best shown by Fig. 17, has outer parallel leg portions 93 and 94 slidably engaging the roller engaging guideway 36 and a shoulder 95 which provides a seat for a coil spring 96. This shoulder is pressed inwardly, as indicated at 97, so as to provide a

projection protruding into the end of the spring. At its opposite end, the spring engages the base of the guideway 36 and at this end, the latter has a struck-out lip 97 that projects into the end of the spring, and thus, by providing the projection 97 and the lip 98, the spring is prevented from slipping out of place. It is apparent that the spring urges the guideway against the rollers in a manner similar to that effected by the leaf spring 82 in Fig. 14. The bases of the brackets 90 and 91 are secured by rivets 99 to a marginal panel 100, which may be suitably secured to the panels 12 and 13.

In Fig. 18, a tilttable carriage similar to that shown by Figs. 14 and 16 may be employed, but in this instance rollers 101 are provided that have grooved peripheries which engage a V-shaped rib 102 in a guideway 103 that extends substantially the height of the door well. This guideway is resiliently movable parallel to the plane of the rollers in channel brackets 104 and 105, each of which is formed by two semi-channel sections 106 and 107 that are fastened by the screws 108 to the marginal door panel indicated at 109.

Jointly the two sections 106 and 107 form a recess 110, which receives a coil spring 111 that urges the guideway 103 against the rollers. It will be understood that vertical movement of the guideway in the brackets 104 and 105 may be prevented by internal lips on the bracket, such as previously described. Each of the brackets 104 and 105 is of the same character and has a spring for resiliently urging the guideway 103 against the rollers.

Although more than one form of the invention has been described and illustrated in detail, it will be apparent to those skilled in the art that various modifications may be made without departing from the scope of the appended claim.

What is claimed is:

In combination in a vehicle door, a vertically movable window, guideways on the door adjacent the front and rear edges of the latter and having converging sides extending in generally vertical directions, guide means on the window and engaging one of the guideways, a tilttable carriage on the window in the plane of the window and having vertically spaced rollers engaging the other guideway, said rollers having converging sides mateable with those of the guideways and spring means relatively urging said guideways towards the rollers to provide the sole means for guiding and retaining the window against movement.

ALFRED H. HABERSTUMP.
